UNITED STATES PATENT OFFICE.

WILLIAM SPALCKHAVER, OF NEW YORK, N. Y., ASSIGNOR TO ROBERT HOE,
THEODORE H. MEAD, AND CHARLES W. CARPENTER, OF SAME PLACE.

CUTTING, FOLDING, AND COLLECTING MECHANISM.

SPECIFICATION forming part of Letters Patent No. 652,817, dated July 3, 1900.

Application filed October 7, 1899. Serial No. 732,854. (No model.)

To all whom it may concern:

Be it known that I, WILLIAM SPALCKHAVER, a citizen of the United States, residing at New York city, county of Kings, and State 5 of New York, have invented certain new and useful Improvements in Cutting, Folding, and Collecting Mechanisms, fully described and represented in the following specification and the accompanying drawing, forming a part 10 of the same.

This invention relates to certain improvements in the cutting and collecting mechanism of fast rotary printing-machines.

In fast rotary printing-machines as now 15 usually constructed one cylinder of the pair of cutting-cylinders also acts as the collecting-cylinder, the heads of the successive sheets being taken by sheet-taking devices, such as pins, and the sheets being cut off in 20 succession by the cutting agencies carried by the cylinders. While the cutting mechanism is intended to cut only each successive sheet, it has been found in actual practice that it 25 operates not only to cut a sheet from the web which is presented to it for that purpose, but it also in many instances cuts a slight shaving or narrow strip from the tail of the preceding sheet which is to be associated with the freshly-cut sheet, this being due either to 30 the fact that the sheet stretches somewhat or becomes in some way displaced. The shavings or thin strips thus cut off are exceedingly troublesome to get rid of, and various devices have been resorted to to prevent this 35 second cutting of the sheet. Such devices have, however, been complicated and expensive, have not been adapted for use with fast machinery, and have not always been reliable in operation.

40 It is the object of this invention to so construct cutting, folding, and collecting mechanisms of a fast rotary press as to enable the successive sheets to be collected and at the same time to keep the tail of the sheet from being a second time cut or clipped by the action of the cutters in cutting the succeeding sheet.

With this and other objects in view the invention consists in certain constructions and 45 in certain parts, improvements, and combinations, as will be hereinafter described and

then pointed out in the claims hereunto appended.

In the accompanying drawing, which forms a part of this specification, and in which like 55 characters of reference indicate the same parts, the figure illustrates a form of cutting and folding mechanism embodying the invention.

Referring to the drawing, 1 indicates a folding-cylinder of the ordinary construction, this cylinder being provided with the usual folding-blades 2, which may be of any desired form and operated in any well-known manner. In the form of the invention shown the 60 cylinder 1 is provided with two knives 3. The number of knives will, however, be varied according to the product to be formed. These knives may also be of any usual construction. The cylinder is further provided with any suitable form of sheet-taking devices. The devices shown are the usual sheet-taking pins, (indicated at 4,) these pins being controlled by cams and spring-rods in the ordinary manner. Inasmuch, however, as the construction 70 and operation of the sheet-taking devices are not material to the invention, said devices have not been fully illustrated.

Coöperating with the cutting and folding cylinder 1 is a cutting-cylinder 5, said cylinder being provided with a block 6, having a cutting-groove therein, which groove coöperates in succession with the knives 3. In this form of the invention this cylinder will be made of a smaller diameter than its companion cylinder, the dimensions shown being as 85 one to four.

In printing-machines as now ordinarily constructed one of the pair of cutting and folding cylinders which have just been described 90 is caused also to act as a collecting-cylinder. The result of this has been that when the first sheet has been taken by the pins on the collecting-cylinder and the pins while carrying this sheet are brought around into position 95 to receive the leading end of the web which is to form a second sheet and a length of web has been superposed on the first sheet the tail of the first sheet becomes so positioned with relation to the cutter that the cutter in cutting off the second sheet also cuts a small trimming or shaving from the tail of 100

the first sheet. To avoid this difficulty, there is provided an independent collecting-cylinder which operates to receive the sheet after it is cut directly from the cutting-cylinder, 5 the sheets being superposed and collected on this independent cylinder.

In the construction shown the independent collecting-cylinder is indicated at 7, said cylinder being provided with any suitable form of 10 sheet-taking devices, as pins 8. In this form of the invention the cylinder is also provided with a small gap 9, which registers with the knives 3 on the cylinder 1, and thus allows the said knives to pass the cylinder 7. It will 15 be readily seen that by taking the sheet directly away from the cutting and folding cylinders and collecting them on an independent cylinder the cutting and folding cylinders can only operate upon one sheet at a time, and 20 therefore the cutting devices carried by them cannot cut the tail of the preceding sheet.

In the construction shown after a given number of sheets have been collected upon the cylinder 7 they are transferred to the cylinder 1 and folded off by the folding-blades 2 between a pair of rollers 10, which coöperate with the said folding-blades. It will be 25 seen that in this construction the cylinder 7 and pins 8 take and collect all of the given 30 number of sheets which are to be folded together except the last sheet. The last sheet remains on the cylinder 1, and the sheets from the cylinder 7 are transferred onto it, after which all the sheets are folded off together.

35 11 and 12 indicate any suitable guide-rolls by which the web is presented to the cutting, folding, and collecting mechanism—as, for instance, the draw-off rolls of a longitudinal folder.

40 Constructions are well known in the art in which a separate associating mechanism—such, for instance, as a collecting-cylinder—is used with a pair of cutting-cylinders, each sheet after being cut by the cutting-cylinders 45 being carried to the associating mechanism or collecting-cylinder by means of tapes. Such mechanisms are, however, cumbersome and unreliable and are not at all adapted for use in a fast rotary press. By arranging the 50 construction, however, so that the independent collecting-cylinder takes the sheet directly from one of the folding-cylinders the intermediate objectionable tape-pathways are done away with and a mechanism is produced 55 which is very compact, a most important point in the construction of large fast presses, which can be run at any desired speed, and which is positive and reliable in its operation. Furthermore, if the invention be embodied in 60 constructions similar to those shown in the drawing one of the cutting-cylinders can be made very small and the mechanism as a whole takes up little, if any, more room in the machine-frame than mechanisms in which 65 one of the cutting-cylinders is used as a collecting-cylinder.

Variations may be made in the construc-

tion by which the invention is carried into effect. The invention is not, therefore, to be limited to the precise details of construction 70 which have been shown and described.

What is claimed is—

1. In a cutting, folding and collecting mechanism, the combination with a pair of cutting-cylinders, one of which is provided with suitable folding-off devices, of a collecting-cylinder independent of the cutting-cylinders, means whereby said collecting-cylinder is caused to take all the sheets of a number to be collected except the last, and means whereby said sheets are retransferred from the collecting-cylinder to the cutting-cylinder to be folded off therefrom, substantially as described. 75

2. In a cutting, folding and collecting mechanism, the combination with a pair of cutting-cylinders, one of said cylinders being provided with sheet-taking devices and folding-off devices, of a collecting-cylinder independent of the cutting-cylinders, said collecting-cylinder being provided with sheet-taking devices, means whereby the sheet-taking devices on the collecting-cylinder are caused to take all of a number of sheets to be collected except the last, and means whereby said sheets are retransferred from the collecting-cylinder to the cutting-cylinder to be folded off therefrom, substantially as described. 80

3. In a cutting, folding and collecting mechanism, the combination with a pair of cutting-cylinders, one of said cylinders having one or more sets of sheet taking and retaining pins and suitable folding-off devices, of an independent collecting-cylinder having sheet taking and retaining pins, means whereby the pins on the collecting-cylinder are caused to take all of a number of sheets to be collected except the last, and means whereby said sheets are retransferred from the collecting-cylinder to the cutting-cylinder to be folded off therefrom, substantially as described. 100

4. In a cutting, folding and collecting mechanism, the combination with suitable web-guides, of a folding-cylinder 1 having cutting-blades, as 3, sheet-retaining pins 4, and folding-blades 2, a coöperating cutting-cylinder 5 of smaller diameter than the cylinder 1 provided with a cutting-block 6, an independent collecting-cylinder 7 having sheet taking and retaining pins 8 and provided with a gap 9, 115 and means whereby the pins 8 are caused to take all of a number of sheets to be collected except the last from the pins 4 and after the sheets are collected retransfer them to said pins 4 to be folded off by the folding-blades 120 2, substantially as described.

5. In a cutting, folding and collecting mechanism, the combination with a pair of cutting-cylinders, one of said cylinders being smaller than the other and the larger cylinder having sheet taking and retaining and folding-off devices, of an independent collecting-cylinder having sheet taking and retaining devices and provided with a gap to permit the cutting de- 130

5 vices on the cutting-cylinder to pass it, the sheet taking and retaining devices on said cylinder, operating to take all of a number of sheets to be collected except the last from the sheet taking and retaining devices on the cutting-cylinder and retransfer them to the cutting-cylinder to be folded off, substantially as described.

In testimony whereof I have hereunto set my hand in the presence of two subscribing to witnesses.

WILLIAM SPALCKHAVER.
